UNITED STATES PATENT OFFICE.

CARL HOLMSTROM, OF LONDON, ENGLAND, ASSIGNOR OF ONE-HALF TO ELIAS MIDDLETON,
OF SHEFFIELD, ENGLAND.

BREECH MECHANISM OF ORDNANCE.

No. 880,994.

Specification of Letters Patent. Patented March 3, 1908.

Application filed July 23, 1906. Serial No. 327,430.

To all whom it may concern:

Be it known that I, CARL HOLMSTROM, a subject of the King of Great Britain, residing at 25 Victoria street, Westminster, in the 5 county of London, England, engineer, have invented certain new and useful Improvements Relating to the Breech Mechanism of Ordnance, of which the following is a specification.

- 10 This invention relates to gun breech mechanism of the kind in which the breech block is provided with a "De Bange" obturator and is rotatably mounted in a swinging carrier pivoted at the side of the breech. At 15 tempts have been made to employ in this class of breech mechanism obturators having little, if any taper, and to furnish means whereby, after the block has been angularly displaced to unlock it from the breech 20 threads, said block will be caused to move a short distance in a rectilinear path, to remove the obturator from its seat and permit of the block being then swung out of the breech chamber by the carrier.
- 25 It is the chief object of my invention to so construct breech mechanism of the above stated character, that great power can be exerted on the block for imparting thereto the aforesaid rectilinear movement by an appropriate arrangement of lever mechanism which 30 will remain inoperative until the unseating effort on the obturator is required to be exerted, whereupon said lever mechanism will exert a powerful rearward pull or toggle-like action 35 on the block which will effectually unseat the obturator. Said mechanism will also operate with equal effectiveness during the inward rectilinear movement of the block and the seating of the obturator.
- 40 The aforesaid lever mechanism may comprise a pair of cranks or arms pivoted to the carrier so as to move in a horizontal plane *i. e.* a plane transverse to that of the face of the breech block, which latter has a pair of 45 flanges or cam grooves thereon for the free ends of the said cranks or arms to engage with. The position of this pair of cranks or arms relatively to the pair of flanges or cam grooves on the block is such that the cranks 50 or arms come into engagement with the flanges or cam grooves as the block completes its angular displacement so that by the continued movement of the cranks or arms about their pivot, the block will experience a powerful rearward pull which will

be exerted through the said flanges or cam grooves, thus exerting on the block a rectilinear pull similar to that which would be produced by a toggle-like arrangement. For imparting motion to the said pair of 60 cranks or arms the swinging carrier is furnished with a movable piece which may be in the form of a sliding bar receiving its motion from suitable mechanism such as a crank and link arrangement which may be 65 operated from the usual gearing at the pivot of the swinging carrier. This movable piece is suitably connected with a crank or arm pivoted to the carrier so as to move in a vertical plane, *i. e.* parallel to the face of the 70 breech block, and engaging with a radial slot on the rear face thereof, so that by the movement of said crank or arm the necessary angular displacement may be imparted to the block for locking or unlocking it to or 75 from the breech threads.

In order that the said invention may be clearly understood and readily carried into effect I will describe the same more fully with reference to the accompanying drawings, in which:—

Figure 1 is an elevation of the breech end of a gun with the improved breech mechanism applied thereto, the parts being in the position they assume when the breech is 85 fully closed. In this arrangement the mechanism is adapted to be actuated by a hand-lever. Fig. 2 is a plan, and Fig. 3 a vertical central section of the same. Fig. 4 is a plan similar to Fig. 2 with the parts in 90 the position they occupy when the block has been unlocked and rectilinearly moved rearwardly. Fig. 5 is an elevation, and Fig. 6 a plan of the improved breech mechanism adapted to be actuated by a hand-wheel instead of by a lever. 95

Like letters of reference indicate similar parts in all the figures.

A is the breech end of the gun, B the breech block, C the obturator, D the obturator-pad, E the swinging carrier and F the breech actuating hand-lever. The aforesaid sliding bar is, in the example shown, made in the form of a double rack a' , a'' , one set of teeth (viz. a') engaging with a toothed 100 segment g , forming part of the crank or arm G which is on the carrier and which imparts the angular movement to the block through the radial slot b thereof. The other set of teeth (viz. a'') is at right angles to the set of 105 110

teeth a' , and engages with a toothed segment h forming part of the pair of cranks or arms H, H . These cranks or arms are carried by a vertical shaft h' on the carrier and impart the rectilinear movement to the block. Their free ends move in a horizontal plane and have anti-friction rollers which move in the direction of the arrow (Fig. 2) to engage with the pair of flanges or grooves b', b' on the rear face of the block and exert a powerful rearward pull on the latter as aforesaid.

In the arrangement illustrated by Figs. 1 to 4 the said double rack is actuated by a link f which is connected at f' to said rack and at f'' to the breech actuating lever which moves about a pivot f^3 on the carrier and in its outward movement brings a tooth or projection f^4 against a lug e on said carrier so that the continued outward movement of the lever causes the carrier to swing about its pivot E' .

In the arrangement illustrated by Figs. 5 and 6 the said double rack is also actuated by a link f but this link instead of being pivoted to the breech actuating lever as in the preceding figures is pivoted to a crank f^5 on the carrier. This crank receives motion through toothed gearing f^6 from the carrier-pivot f^7 to which the breech actuating hand wheel f^8 is geared by a worm f^9 and worm wheel f^{10} .

A suitable catch may be provided for retaining the block in its position of disengagement with the crank G , during the time that the carrier is being swung to and from the breech opening. This catch may comprise a sliding bolt i carried by the carrier and having an inclined nose i^1 ; it may be provided with a lateral spring i^2 for exerting sufficient friction thereon to prevent it from unintentional movement. The said bolt may also have an incline i^3 for a corresponding projection i^4 on the gun-breech to act upon during the closing movement of the carrier.

Instead of arranging the aforesaid cranks or arms H, H to move in a horizontal plane as above stated, they may be arranged to move in any other suitable plane transverse to that of the face of the breech block and the motion may be imparted to them from bevel gearing or the like. In some cases also only one of the cranks or arms H and one of the flanges or grooves b' need be employed.

What I claim and desire to secure by Letters Patent of the United States is:—

1. In gun breech mechanism of the De Bange obturator type, the combination with the swinging carrier and the breech block movably mounted thereon, of means for imparting angular motion to said block, lever mechanism turning about a fulcrum situated immediately behind the face of the breech block for rectilinearly moving the said block

in the carrier, means for swinging the carrier about its pivot, and means whereby these various movements take place in proper sequence by the continued movement of the member by which the force for working the mechanism is applied thereto. 70

2. In gun breech mechanism of the De Bange obturator type, the combination with the swinging carrier and the breech block movably mounted thereon, of means for imparting angular motion to said block, an arm or crank mounted on the carrier to move about a fulcrum situated immediately behind the face of the breech block in a plane transverse with respect to the rear face of the said block, a flange on said block with which the arm or crank engages to move the block in a rectilinear path, means for operating said arm or crank, means for swinging the carrier about its pivot, and means whereby these various movements take place in proper sequence by the continued movement of the member by which the force for working the mechanism is applied thereto. 75 80 85

3. In gun breech mechanism of the De Bange obturator type, the combination with the swinging carrier and the breech block movably mounted thereon, of means for imparting angular motion to said block, an arm or crank mounted on the carrier to move in a plane transverse with respect to the rear face of the block, a flange on said block with which the arm or crank engages to move the block in a rectilinear path, toothed gearing for actuating said arm or crank, means for swinging the carrier about its pivot, and means whereby these various movements take place in proper sequence by the continued movement of the member by which the force for working the mechanism is applied thereto. 90 95 100 105

4. In gun breech mechanism of the De Bange obturator type, the combination with the swinging carrier and the breech block movably mounted thereon, of a crank mounted on the carrier to move in a plane parallel with the rear face of the block and engaging with a radial slot of the latter to angularly displace the same, a pair of arms or cranks mounted on the carrier to move in a plane transverse with respect to the face of the block, flanges on the block with which the pair of arms or cranks engage to shift the block rectilinearly, means for actuating the aforesaid cranks, means for swinging the carrier about its pivot, and means whereby these various movements take place in proper sequence by the continued movement of the member by which the force for working the mechanism is applied thereto. 110 115 120 125

5. In gun breech mechanism of the De Bange obturator type, the combination with the swinging carrier and the breech block movably mounted thereon, of a crank mounted on the carrier to move in a plane

parallel with the rear face of the block and engaging with a radial slot of the latter to angularly displace the same, a pair of arms or cranks mounted on the carrier to move in a plane transverse with respect to the face of the block, flanges on the block with which the pair of arms engage to shift the block rectilinearly, a sliding rack bar on the carrier for actuating the crank that engages with the radial slot on the block and the cranks or arms that engage with the flanges on the block, means for actuating said rack bar, and means whereby these various movements take place in proper sequence by the continued movement of the member by which the force for working the mechanism is applied thereto.

6. In gun breech mechanism of the De Bange obturator type, the combination with the swinging carrier and the breech block movably mounted thereon, of a crank mounted on the carrier to move in a plane parallel with the rear face of the block and engaging with a radial slot of the latter to angularly displace the same, a pair of arms

or cranks mounted on the carrier to move in a plane transverse with respect to the face of the block, flanges on the block with which the pair of arms engage to shift the block rectilinearly, a sliding rack bar on the carrier having two sets of teeth, a toothed segment engaging with one set of the teeth and imparting motion to the crank that turns the block, a toothed segment engaging with the other set of teeth and imparting motion to the cranks or arms that rectilinearly shift the block, lever mechanism for operating the said sliding rack bar, a crank on the carrier for operating the lever mechanism, and means for operating said crank by the movement of the member by which the force for working the mechanism is applied thereto.

In testimony whereof I have hereunto set my hand in presence of two subscribing witnesses this twelfth day of July 1906.

CARL HOLMSTROM.
